UNITED STATES PATENT OFFICE.

DANIEL D. MOUNTS, OF LOS ANGELES, CALIFORNIA.

PHONOGRAPH.

Application filed March 8, 1927. Serial No. 173,674.

This invention relates to phonographs, and has for its object an arrangement whereby the diaphragm of the sound box is at right angles and substantially in alinement with the axis of the amplifying horn in order to obtain maximum sound with minimum distortion.

It is a further object of the invention to eliminate the use of a movable tone arm and connect the sound box directly to a fixed amplifying horn with the necessary radial movement between the turn-table and the sound box obtained by arcuate swinging of the turn-table relative to the fixed sound box.

It is a still further object of the invention to provide driving mechanism for the swinging turn-table, of extremely simple construction and adapted to counterbalance the turn-table so that it may freely swing responsive to the travel of the stylus of the fixed sound box along the groove of the reproducing record.

Further objects of the invention will be readily understood from the following description of the accompanying drawings, in which:

Fig. 1 is a rear elevation of the construction.

Fig. 2 is a plan view, showing in dotted lines the arcuate swing of the turn-table to accommodate itself to the travel of the stylus of the fixed sound box along the groove of the reproducing record.

Fig. 3 is a side elevation with the turn-table swung to the position shown in dotted lines in Fig. 2.

The turn-table 1 and its driving mechanism which may be an electric motor 2, are mounted on opposite ends of a horizontal arm 3 having a vertical pivot 4 intermediate of its ends, whereby the driving mechanism and the turn-table counterbalance one another to permit free turning of arm 3 on its pivot.

The pivotal mounting includes a bearing 5 in a supporting block 6 and suitable anti-frictional means 7 to insure free arcuate swinging of arm 3 responsive to the travel of the stylus of a fixed sound box along the groove of the usual reproducing record mounted on the turn-table.

Turn-table 1 is adapted to revolve freely, and for this purpose has a depending pivot 10 journaled in a vertical bearing 11 at the end of arm 3, preferably with anti-frictional means 12 at the bearing. The turn-table is also provided with the usual stud 12^a at its

upper surface adapted to center the usual reproducing record 13 which is mounted on the turn-table for rotation therewith.

The driving connection between motor 2 and the turn-table comprises a friction disc 14 engaging the underside of table 1 near its outer periphery and fixed on the shaft 15 of the motor, the motor 2 being mounted so that its shaft is parallel to arm 3 with disc 14 in vertical position as shown in Figs. 1 and 2.

The amplifying horn 20 of the phonograph is rigidly supported as shown at 21, and the usual sound box 22 is fixed at right angles and in substantial alinement with the axis of the horn as shown in Figs. 2 and 3, the parts being arranged for travel of stylus 23 of the fixed sound box along the groove of record 13 in usual manner as a result of the free arcuate swinging of the turn-table.

The sound box may be raised and lowered slightly for engaging the stylus in the groove of the record, and for this purpose the sound box has a tone arm 24 projecting at right angles therefrom, the tone arm being adapted for limited pivotal movement on a horizontal axis in a cooperating coupling 25 at the inner end of horn 20, the parts being so arranged that sound is transmitted directly from the sound box into the horn along substantially a straight line as shown in Figs. 2 and 3.

I thus eliminate distortion and obtain maximum sound reproduction, since the sound box is fixed at right angles to the axis of the amplifying horn and communicates directly therewith along a substantially straight line, the necessary radial movement between the reproducing record and the fixed sound box being obtained by arcuate swinging of the turn-table in response to the travel of the stylus along the groove of the reproducing record mounted on the turn-table.

I claim:

1. In a phonograph, a supporting arm pivoted intermediate of its ends, a turn-table on one end of the arm, rotary drive mechanism mounted on the opposite end of the arm so as to counterbalance the turn-table, a frictional driving connection between the drive mechanism and the turn-table, and a stationary sound box having a stylus adapted to engage the groove of a reproducing record mounted on the turn-table for swinging the supporting arm so as to radially move the reproducing record relative to the stationary sound box in

accordance with travel of the stylus along the groove of the record.

2. In a phonograph, a supporting arm pivoted intermediate of its ends, a turn-table mounted on one end of the arm, rotary drive mechanism mounted on the opposite end of the arm so as to counterbalance the turn-table, a driving connection between the drive mechanism and the turn-table, and a stationary sound box having a stylus adapted to engage

the groove of a reproducing record mounted on the turn-table for swinging the supporting arm so as to radially move the reproducing record relative to the stationary sound box in accordance with travel of the stylus along the groove of the record. 5

In testimony whereof he has affixed his signature to this specification.

DANIEL D. MOUNTS
